ABSTRACT

Disclosed are compositions comprised of fine particles

of unannealed poly(1,4-cyclohexylenedimethylene terephthalate) dispersed in a poly(tetramethylene terephthalate) type polyester, a poly(pentamethylene terephthalate) type polyester, a poly(hexamethylene terephthalate) type polyester, a poly(1,4-cyclohexylenedimethylene terephthalate/isophthalate) type polyester, a poly(tetramethylene terephthalate) type polyester modified with poly(alkylene oxide)-glycol, a poly(1,4-cyclohexylenedimethylene terephthalate) type polyester modified with poly(alkylene oxide) glycol or a polyester prepared from 1,4-cyclohexanedicarboxylic acid, dimer acid, and 1,4-cyclohexanedimethanol.
